UNITED STATES PATENT OFFICE.

BERNHART A. BENSON, OF CHICAGO, ILLINOIS, ASSIGNOR TO CHICAGO ELECTRIC MANUFACTURING CO., OF CHICAGO, ILLINOIS, A CORPORATION OF ILLINOIS.

PUSH AND PULL SWITCH.

Application filed March 18, 1925. Serial No. 16,398.

My invention relates to electric switches of the push and pull type, and in its general objects aims to provide an unusually simple and inexpensive switch construction in which certain of the parts are retained in their operative positions by the mere assembling of the switch without requiring fastening elements for securing these parts to each other. It also aims to provide a switch construction in which the movable contact carrier is mounted with freedom for movement relatively to both the actuating plunger and the stationary contacts, so as to permit it to adjust itself to any lack of alignment and to deviations in the shape of adjacent parts.

More particularly, my invention provides a switch in which the stationary contacts are disposed at opposite sides of a continuation of the axis of a reciprocable plunger, provides an insulating contact carrier slidably movable between the two stationary contact members and guided at its ends by the walls of the casing, and provides this carrier and the plunger with formations adapted to be engaged by a simple relative transverse movement of these parts during the assembling of the switch. It also provides a switch construction of this type in which an insulating contact carrier is disposed for engaging the ends of the casing so as to limit the movement of this carrier and of the actuating plunger in both directions, thereby permitting the use of a plunger which can be inserted from the back of the switch and which will have no exposed portion of greater diameter than the threaded supporting nipple through which the plunger extends, and also permitting the casing to hold the contact carrier interlocked with the plunger before the terminal carrying base end of the casing is placed in position.

Furthermore, my invention provides a switch in which the contact carrier can readily be formed of a single and simple punching and in which a material like vulcanized fiber can be employed for this purpose without having a swelling or warping of this material interfere with the operation of the switch. It also provides a switch in which the contact arms normally prevent the contact carrier from disengagement with the plunger, in which these arms yieldingly hold the contact carrier in either the "on" or "off" position of the switch, in which casing por-

tions afford positive stops for limiting the movement of the contact carrier in both directions, and in which this limiting does not prevent the contact arms from readjusting the "on" position of the carrier to one affording good electrical connections. Still further and also more detailed objects of my invention will appear from the following specification and from the accompanying drawings, in which

Fig. 1 is a central and longitudinal section of a switch embodying my invention, drawn with the parts in the circuit-closing or "on" position.

Fig. 2 is a similar section taken at right angles to Fig. 1.

Fig. 3 is a section similar to Fig. 1, but showing the operating parts in the "off" or circuit-opening position.

Fig. 4 is a bottom view of the switch.

Fig. 5 is an enlarged perspective view of the insulating contact carrier of the switch.

Fig. 6 is a perspective view of the insulating base.

Fig. 7 is an enlarged central and longitudinal section through the forward end of one of the contact arms.

Fig. 8 is a fragmentary section taken from the line 8—8 of Fig. 2 to show the position of one end of the contact carrier with respect to the lateral casing wall.

In the illustrated embodiment, the housing of the switch comprises a rearwardly open metal casing having a cylindrical side wall 1 and a centrally perforated forward end 2, which end has a forwardly extending threaded nipple 3 secured to it, so that the casing can be clamped against a suitable support, such as a dashboard 5 by a nut 6 threaded upon the nipple.

Closing the rear end of the casing is an insulating base 7, here shown as abutting against the rear end of the lateral casing wall 1 and as provided on its periphery with a number of recesses 23 each housing a rearwardly projecting finger 22 on the said wall 1, the tips of these fingers 8 being bent over the back of the insulating base 7 so as to secure the base firmly to the main metal member of the casing.

Mounted on the insulating base 7 are a pair of contact members each of which has a foot 9 riveted to the back of the base and carrying a bolt 10 by means of which the free end of a circuit wire 11 is secured to

this foot. Each of the said terminal members also includes a contact arm 12 which extends through a perforation 23' in the base 7, the two contact arms being disposed at 5 opposite sides of the axis of the cylindrical casing. These contact arms 12 desirably are bowed away from each other and have their free end portions formed into opposed bights convexed towards each other after the man- 10 ner shown in Fig. 1.

For the movable contact member of the switch I provide a metal part, desirably in the form of a hollow rivet 13 extending transversely through a carrier 14 made of 15 insulating material. This carrier is slightly shorter transversely of the axis of the switch casing than the bore of this casing and has its rear portion continuously disposed between the contact arms 12, so that 20 these arms normally maintain its medial plane 15 substantially in the axis of the switch casing.

To move the carrier and the contact member 13 mounted on the latter, I provide a 25 plunger 16 which extends slidably through the bore of the nipple 3 and which desirably has its forward end 17 formed to afford a knob by means of which the plunger can be digitally moved in both directions. The 30 rear end of the plunger and the forward end of the carrier 14 are provided with interlocking formations, for which purpose I desirably form a groove 28 in the plunger near its rear end and provide the forward 35 end of the carrier with a central and longitudinal slot spacing a pair of opposed fingers 19 which enter the said groove and which are adapted to engage the opposite walls of the groove to limit the relative 40 movement of the carrier and the plunger longitudinally of the switch. I also provide the carrier 14 with a recess formation into which the bights of the contact arms 12 can extend towards each other when the carrier 45 is in its rearward position as shown in Fig. 3, for which purpose I desirably enlarge the said slot between the fingers 19 rearwardly of the latter to a width somewhat greater than that of the contact arms 12, after the 50 manner of the perforation 24 of Fig. 5, so that this perforation normally houses the part of the head 27 back of the fingers 19.

With the parts thus constructed and with the knob 17 of the plunger formed of a 55 diameter not greater than the main portion 16 of this plunger, the fingers 19 of the contact carrier can readily be inserted in the groove on the plunger by a relative transverse movement of these parts before the 60 plunger is slipped through the bore of the nipple 3 from the rear of the switch casing. When thus inserted, the approaching of the width of the carrier to the bore of the switch casing will cause the latter to hold 65 the carrier substantially diametric of the

casing. The base member of the switch, comprising the insulating base 7 with the two stationary contact members already secured to it by rivets 25, can then be slipped into position with its contact arms 12 70 straddling the carrier and with the casing fingers 22 extending through the corresponding perforations 23 in the base 7. The tips of the fingers 23 are then turned over the back of the base 7, thereby completely assembling the switch. 75

By forming the contact arms 12 so that their normal resiliency will make their bights to approach to a distance less than the thickness of the carrier 14, I cause these 80 bights to clamp the movable contact 13 firmly between them when the plunger has moved the carrier to a certain position. This position is desirably fixed by providing each of the bights with a boss 26 directed toward the other bight and adapted to snap into the adjacent end of the tubular contact member 13, thereby latching the carrier as well as the plunger against accidental movement out of the "on" position 90 of the switch. Then I make the carrier 14 of such a length that its rear end will abut against the forward face of the insulating base 7 when the bights of the contact members have partly entered the enlarged slot 95 20 of the contact member, as shown in Fig. 3 so that the engagement of the carrier with the base of the switch will positively limit the rearward movement of the carrier and plunger. At the same time, the 100 engagement of the bights of the two contact arms with rear wall portions of the slot 20 (which form shoulders engaged by the contact arms) will hold the contact carrier against accidental forward movement. I 105 also desirably make the distance between the movable contact 13 and the forward end of the carrier 14 of a length slightly less than the distance between the said bosses 21 on the bights of the contact arms and a front 110 portion of the casing, so that the carrier can engage this front portion to afford a positive stop for limiting the forward movement of the carrier and plunger, while permitting the clamping action of the contact 115 arms to retract the carrier slightly into a position in which their bosses 26 are socketed in the ends of the tubular contact member 13. 120

With the switch thus arranged, it will be seen that both the construction and assembling of the switch are unusually simple, even the cost of the plunger being reduced in comparison with the usual construction since no formations of an enlarged diameter are required to serve as stop formations, so that the plunger can be turned from smaller stock. Since the resiliency of the contact arms will readily permit them to adjust themselves to variations in the length 125 130

of the movable contact member 13, a great exactness in the proportioning of the parts is not required. Indeed, the fingers 19 can have a fairly loose fit in the plunger groove 5 entered by them and the carrier does not need to fit the bore of the casing closely, so that any swelling or warping of this carrier will not interfere with the operation of the switch.

10 By disposing the lateral ends of the carrier 14 adjacent to the lateral casing wall, I enable this wall to prevent the carrier from tilting or sliding transversely of its flat faces to such an extent as would disengage the 15 interlocking of the carrier with the plunger. Consequently, the casing will hold the carrier substantially in its normal position before the base member of the switch (namely, the insulating base 7 and the circuit terminal 20 members which are mounted on this base and which include the contact arms 12) is slipped into position. In practice, the casing wall serves this purpose without requiring the lateral carrier ends to touch the casing in 25 the assembled switch and without requiring a close fit between the interengaging parts of the carrier and plunger, so that the carrier can slide or tilt slightly transversely of the plunger in permitting the contact arms 30 to adjust themselves to firm contacting positions.

However, while I have illustrated and described my invention in a switch supported from its front and one having desirable 35 shapes of various parts, I do not wish to be limited to the details of construction and arrangement thus disclosed. Obviously, many changes might be made without departing either from the spirit of my invention or from the appended claims.

40 I claim as my invention:—

1. An electric switch including a casing having opposed end walls, a pair of spring contact arms in the casing, an insulating member having a slot adjacent one end thereof, a contact element between the slot and the opposite end of the member, and operating means for said member engageable in 45 said slot, said arms being formed with parts which in one position of the member engage the wall defining the inner end of the slot thereby to hold the said opposite end of the member engaged with the inner face of one end wall of the casing, said operating 50 means extending through the other end wall of the casing.

2. An electric switch including a casing having opposed end walls, a pair of spring contact arms in the casing, an insulating member 55 loosely disposed within the casing and having a slot adjacent one end thereof, a contact element between the slot and the opposite end of the member, and operating means for said member engageable in said

slot, said arms being formed with parts 60 which in one position of the member engage the wall defining the inner end of the slot thereby to hold the said opposite end of the member engaged with the inner face of one end wall of the casing, said operating means 70 extending through the other end wall of the casing.

3. An electric switch including a casing having an end wall, a pair of spring contact arms in the casing, an insulating member loosely disposed within the casing and having a slot extending from an intermediate point lengthwise of the member and through an end thereof, a contact element 75 between the slot and the opposite end of the member, and operating means for said member having a part thereof extending into the slot, said arms being formed with parts which in one position of the member engage the wall defining the inner end of the slot thereby to hold the said opposite end of the member engaged with the end wall of the casing.

4. An electric switch including a casing having an end wall, a pair of spring contact arms in the casing, an insulating member loosely supported within the casing and having a substantially V-shaped slot extending from an intermediate point lengthwise of the member and through an end thereof, a contact element between the slot and the opposite end of the member, and operating means for said member having a part loosely extending into the slot, said arms being formed with parts which in one position of the member engage with each of the walls defining the inner end of the V-shaped slot thereby to hold the said opposite end of the member engaged with the end wall of the casing.

5. An electric switch including a casing, a pair of spring contact arms in the casing, an insulating member movable in said casing and having a contact, said member being loosely supported at one end by the arms, operating means for the member, and means to loosely connect the opposite end of the member to the operating means whereby to allow the member to move vertically and to rock so as to permit the contacts of the arms to make electrical contact with the contact of the member.

6. In an electric switch, a casing having an end, contact arms therein, an insulating member in the casing having a pair of walls which diverge relative to said end of the casing and operating means for the member, said arms engaging the respective divergent walls so as to force and hold the member against said end of the casing.

Signed at Chicago, Illinois, March 6th, 1925.
